UNITED STATES PATENT OFFICE.

JOHN CAMPBELL McINTOSH, OF THE GLEN, BY PAISLEY, SCOTLAND.

VALVE-GEAR FOR INTERNAL-COMBUSTION ENGINES.

1,258,583.

Specification of Letters Patent.

Patented Mar. 5, 1918.

Original application filed December 20, 1909, Serial No. 534,168. Divided and this application filed January 16, 1913, Serial No. 742,357. Renewed July 26, 1917. Serial No. 183,018.

To all whom it may concern:

Be it known that I, JOHN CAMPBELL McINTOSH, a subject of the King of Great Britain, residing in Glenhall, The Glen, by Paisley, Scotland, have invented certain new and useful Improvements in Valve-Gears for Internal-Combustion Engines, of which the following is a specification.

This application relates to improvements in valves and valve gear for four cycle internal combustion engines and constitutes a division of my copending application Serial Number 534,168 filed December 20, 1909.

As disclosed in my said prior application my improved engine comprises two reciprocating cylindrical valve sleeves arranged concentrically with the working cylinders and my present application relates particularly to the mechanism for operating such valve sleeves and has for its object to provide a simple, efficient and easily accessible mechanism for this purpose.

A further object of the invention is to provide a valve mechanism of this type for multiple cylinder engines so constructed that the valve sleeves and their operating devices of any one or more cylinders may be easily removed for examination or other purposes without disturbing the other cylinders or their working parts.

In the accompanying drawings forming part of this application, I have illustrated a preferred embodiment of my invention and in the said drawings,

Figure 1 is a vertical sectional view of a single cylinder of a slide valve motor embodying my invention.

Fig. 2 is a plan view of a four cylinder motor embodying the same.

Fig. 3 is a side elevation partly in section of the upper part of the motor shown in Fig. 2.

Fig. 4 is a detail view showing the inner sleeve in side and end elevation, and

Fig. 5 is a similar view of the outer sleeve.

Referring now to the drawings in which like reference characters indicate like parts throughout the several views, A indicates the main shaft mounted in the usual manner in the crank chamber V of the motor. Each cylinder, S, S' of the motor comprises a lower portion having a water jacket R enclosing a liner M which forms the working

wall of the water jacket R is offset from the upper part of the liner M forming an annular cavity U in which the valve sleeves G and H reciprocate. Above the liner M is the cylinder head D, whose lower portion is of an external diameter equal to that of the liner and forms a gas tight engagement with the liner at the point M' just above the ports O of the liner. Immediately below the ports O the liner M is provided with compression rings Q and the cylinder head D is provided with similar rings P surrounding its lower end. The sleeves G and H are formed with ports O corresponding with the ports of the liner M and are of just sufficient length for their lower ends G² and H² to extend below the rings Q and their upper ends to project above the rings P. The upper ends of the water jacketed heads D of the cylinders are coextensive with the water jackets R except for cavities K formed in their adjacent ends D' D' and are detachably bolted to the water jackets along their longitudinal edges to have water connection therewith as will be readily understood. The cavities K which are closed at the bottom by the bridges R' of the water jacket are provided for the reception of the valve sleeve operating mechanism which will now be described. As shown more particularly in Figs. 2 and 3 the cavities K of each cylinder head register with those of the adjacent cylinders to form pockets closed on all four sides and at the ends K² of these pockets adjacent the central depression of the cylinder heads, bearings C' C² are provided for the valve operating shaft C which extends across the tops of the cylinders along their median longitudinal axis. The shaft C is driven from the main shaft A through suitable skew or other gears A' and a vertical spindle B. The shaft C is preferably made up of a plurality of sections, one for each cylinder, joined together by couplings X in line with the abutting ends of the cylinders, and over the pockets K, the ends of each shaft section are provided with cranks E, F, to which are connected the rods J, J, which are pivoted at their lower ends on trunnions G² H² formed on upward extensions G' H' from the opposite sides of the valve sleeves G, H respectively. The shaft C is completely enclosed by detachable covers K' on its upper side and by bridges T beneath, which ex-

tend over the central depressions in the cylinder heads in which are provided the sockets L for the usual spark plugs.

For lubricating the valve sleeves the annular cavities U are connected by suitable bores indicated by dotted lines W with the crank case at W'. The lubricant may be fed to the sleeves through the bores W by a suitable force feed or may be fed directly to the cavities U and allowed to drain through the bores.

For admitting the explosive charge to the cylinders the usual induction ports Y, with flanges Y' extend through the water jackets in line with the ports O on one side and similar exhaust ports, not shown are provided on the opposite side as will be understood.

My improved motor operates on the well known principle of prior sleeve valve engines, the two sleeves co-operating to open the exhaust port on one up stroke of the piston and the intake port on the succeeding down stroke while maintaining both parts closed during the compression and driving strokes.

The advantages of my improved valve operating gear over prior constructions will be obvious from the foregoing description. In the first place by having the operating shaft across the top of the motor the operating connections are instantly accessible for repairs or adjustment, by simply removing the covers K' which may in fact be entirely dispensed with. Secondly, by detaching the cylinder head and couplings X of any cylinder the entire valve mechanism for that cylinder may be removed without disturbing the adjacent cylinders. Furthermore, the pockets formed by the abutting cavities K may be kept full of oil affording perfect lubrication for the parts and the crank case is free of all extraneous parts permitting easy accessibility to the crank shaft connections.

Having thus described my invention what I claim as new and desire to secure by Letters Patent is:

1. In an engine of the class described the combination of a cylinder, a piston working therein, a main shaft operated thereby, a plurality of concentric valve sleeves surrounding said cylinder and having diametrically disposed projections, and means for reciprocating said valve sleeves comprising a shaft at the end of said cylinder opposite from said main shaft and actuating connections between said shaft and each of said projections whereby opposite sides of said cylinders are moved in unison.

2. In an engine of the class described, the combination of a plurality of parallel cylinders, pistons working therein, a main

shaft driven by said pistons, inner and outer valve sleeves surrounding said cylinders and means for operating said valve sleeves comprising a shaft at the ends of said cylinder opposite from said main shaft, said shaft being made up of detachable sections one for each cylinder and a pair of connections adjacent each end of each shaft section operatively connected thereto, and one connection of each pair being connected to one of the valve sleeves.

3. In an engine of the class described, the combination of a cylinder head, a piston movable with respect to said cylinder head, a shaft operatively connected with said piston, a secondary shaft at the combustion end, an inner and outer valve sleeve, connections between each of said sleeves and said secondary shaft, said secondary shaft exposed so as to provide access to said connection.

4. In an engine of the class described the combination of a cylinder head, a piston slidable with respect to said cylinder head, a shaft operatively connected with said piston, a secondary shaft at the combustion end in driving connection with said first named shaft, valve sleeves, means for connecting said valve sleeves with said secondary shaft, said means engaging said sleeves on a plurality of points on the circumference thereof, and a casing for said last named shaft.

5. In an engine of the class described the combination of a cylinder head, a piston movable with respect to said cylinder head, a shaft operatively connected with said piston, a secondary shaft at the combustion end in driving relation with said first named shaft, valve sleeves, means for connecting said valve sleeves with said secondary shaft, said means engaging said sleeves on a plurality of points on the circumference thereof, a casing for said last named shaft, and a casing inclosing said connecting means, said casings being in communication with each other.

6. In an engine of the class described, the combination with a cylinder head, a pair of telescoping valve sleeves surrounding said cylinder head, a shaft journaled above said head and extending radially thereof, said shaft provided with four cranks arranged in pairs on opposite sides of the cylinder head and rods connecting the cranks with the valve sleeves.

In witness whereof, I have hereunto set my hand at Glasgow, Scotland, this 24th day of December, 1912.

J. CAMPBELL McINTOSH.
